ARRESTING MEANS FOR AUTOGRAPHIC
REGISTERS

Harry J. Waechter, Mount Healthy, Ohio, assignor to Paul Benninghofen and Eleanor C. Diesbach, Hamilton, Ohio, as trustees

Application March 11, 1949, Serial No. 80,890

1 Claim. (Cl. 282—12)

1

This invention relates to autographic registers of the type used by salespeople to record sales transactions and other data. In this type of register, a strip of connected manifold forms is serially fed across a writing platen so that single forms are successively exposed to the salesperson who writes the data incident to a single sales transaction on the exposed form. This invention is particularly directed to improvements in the pins which arrest the movement of the strip and align the exposed form on the platen.

In manually operated machines of this type, the folded strip of connected forms is usually stored in an appropriate compartment in the register casing. The end of the strip is unfolded and passed over the writing platen, where the endmost form is aligned on the platen and held in exposed position, by means of spring-mounted pins which engage filing holes in the form. When a sale is made, the salesperson records the transaction on the exposed form, causes the pins to be withdrawn from engagement with the filing holes and grasps the free edge of the form. By pulling on the free edge of the filled-in form, he draws the strip across the platen, until the filled-in form is free of the platen and the following form is moved to the exposed position on the platen where it is held by means of the pins, which are actuated to move into engagement with the filing holes on that form. The filled-in form is then disconnected from the strip by the operator who tears the strip along the scored lines which connect the forms.

The locating pins which align the exposed form on the platen serve to arrest the movement of the strip across the platen when the following form reaches a position of registry with the platen. Usually, these pins are spring-mounted so that, once they are disengaged from the filing holes in the end form and movement of the strip across the platen is started, the springs urge the pins toward the aperture engaging position. Consequently, at least one pin rides the surface of the moving strip until the apertures of the following form come into alignment with the pin, at which time the pin is snapped into engagement with the aperture and the movement of the strip arrested.

Unfortunately, some operators often pull the strip so rapidly across the platen that the filing holes pass over the pins before they can snap into position to stop the movement. Consequently, the operator may find that he has drawn two or three or even more forms from the machine and that he has to open the register, re-fold and pack

2

the forms and place the correct form on the writing platen to save the unmarked forms, inadvertently drawn from the register.

In the past, it has been customary to form the top of the arresting pin so that it is substantially flat or slightly rounded. Thus, when the filing holes move toward the position of registry with the pins, the rearward portion of the pin head rides on the surface of the strip, while the forward portion of the pin head partially registers with the hole. Hence, the rearward portion of the pin head prevents the pin from snapping into engagement with the hole until the entire pin is in exact alignment with the filing hole. Since the movement of these pins is usually accomplished by means of springs of medium strength and sensitivity, the strip movement may be so rapid that the front edge of the pin has engaged the strip on the other side of the filing hole before the springs can urge the pin into engagement with the edge of the hole. Hence, the filing holes on two or three successive forms may pass over the pin before the operator becomes aware of the overtravel. The problem is not so acute in crank operated machines because means are usually provided to temporarily stop the movement of the crank after one complete cycle and the pins engage the holes during the stoppage.

30 The principal object of this invention has been to provide an improved strip-riding arresting pin which will engage the aperture of a moving form and arrest the movement of the form, even though the form is moving at an extremely rapid speed rate.

35 Other objects and advantages of this invention will become apparent to those skilled in the art from the following description of the drawings in which:

40 Figure 1 is a top perspective view of an autographic register incorporating the improved pin of this invention.

45 Figure 2 is a vertical section taken along line 2—2 of Figure 1.

Figure 3 is a vertical section taken along line 3—3 of Figure 2.

50 Figure 4 is a vertical section taken along line 4—4 of Figure 2, showing a typical pin actuating mechanism useful in conjunction with the pin of this invention with the pins engaged in arresting position.

Figure 5 is a view similar to Figure 4, showing the pins in the depressed position.

55 Figure 6 is a fragmentary sectional view taken

similar to Figure 2 but illustrating the pin being depressed.

Figure 7 is a view taken on line 7—7 of Figure 1, but showing the arresting pin in a disengaged position to correspond with the other pin as shown in Figure 6.

Figure 8 is a vertical sectional view similar to Figure 7, showing the pin about to move into an arresting position.

Figure 9 is a vertical section similar to Figure 7, but showing the arresting pin in its engaging position.

The improvements of this invention can be adapted to various types of hand and crank operated autographic registers. However, the invention is disclosed in the drawings in conjunction with an autographic register which is the subject matter of my co-pending application Serial No. 81,565, filed March 15, 1949.

The register consists of a casing indicated generally at 15, comprising a hinged bottom 16, side and end walls 17 and 18, and a hinged frame-type lid 19. The interior of the casing is divided by a platform 20, into a compartment 21, in which a strip of manifold forms 22 is stored, and a compartment 23 which is used as a temporary filing receptacle for duplicate copies of the forms.

As best seen in Figure 2, the manifold strip 22 is partially unfolded and passed around a bar 24 and over a writing platen 25. Depressible pins 26 and 27 project through slots 28 and 29 in the writing platen and engage filing holes 30 in the endmost form of the strip, thus preventing the form from being drawn backwardly across the platen by the weight of the strip and serving to align the form on the platen so that it is exposed through a window 31 in the lid. Clearance slots 32 and 33 in the lid may also be provided to allow the pins to project beyond the top of the forms. The pins 26 and 27 may be withdrawn from engagement with the filing holes to permit a filled-in form to be passed across the platen and drawn from the register.

Suitable mechanism is provided in the register to return the pins to engagement position when the filing holes of the following form in the strip come into registry with the pins. This mechanism snaps the pins upwardly through the slots 28 and 29 in the writing platen and into engagement with the filing hole 30 in the form, thereby arresting the movement of the strip along the platen.

A representative pin actuating mechanism is shown in Figures 3, 4 and 5. This mechanism is preferred since it effects simultaneous withdrawal of both pins and gives eminently satisfactory results. However, it should be understood that any other suitable pin actuating mechanism may be employed with the invention. The pins 26 and 27 are mounted at the ends of arms 34 and 35 which are respectively pivoted on pins 36 and 37 fixed on the opposite side portions of a bracket 38 fastened to platform 15. A tension spring 39 extends between the two arms, being fastened to anchor pins 40 and 41 arranged near the central portion of each arm. This spring tends to urge both of the arms and the arresting pins upwardly in arcuate movement about the pivot points 36 and 37. Stop lips 42 and 43 are provided on the bracket 38 and the upward movement of the levers and the arresting pins is stopped when the abutments 44 on the levers contact these lips.

In order to obtain coactive movement of the

arms, arm 35 is provided with a cam stud 45 which extends through an obliquely angled cam slot 46 formed in arm 34. The projecting end of this stud is upset to provide an annular flange 47 which embraces the backface of arm 34, thus preventing the stud from being sprung out of engagement with the slot. The bracket 38 is cut-out at 48, to receive the flange and the flange is free to move in the cut-out portion without rubbing or interfering with the bracket. Hence, it will be observed that when pin 26 is depressed from engagement with the form holes by means of a pencil 49 or other suitable instrument, arm 34 pivots about pin 36 and cam slot 46 forces cam stud 45 downwardly, thereby causing the simultaneously downward movement of arm 35 and the withdrawal of pin 27 from engagement with the apertures. During this motion, stud 45 slides in slot 46 and tension spring 39 is expanded by the diverging movement of anchor pins 40 and 41. When the pencil is removed and pin 26 released, spring 39 is free to recontract and does so, forcing arms 34 and 35 to pivot upwardly moving the pins toward the arm resting position.

The pins 26 and 27 are of different configuration, pin 26 being constructed in such a manner that it sockets the pencil and permits the pencil to be slid forwardly, forcing the form over the writing platen until an edge of the form projects beyond the casing, thus giving the operator a finger hold on the form. As best seen in Figures 5 and 6, the head of this pin is configured to provide a socket 50 which receives the point of the pencil or other instrument. A ledge 51 extending from the bottom of the pin head is grooved to provide a channel or slide-way 52 co-extensive with the bottom of the socket and along which the pencil point may be drawn. Since the slots 28 and 32 in the platen and lid, respectively, are elongated and do not interfere with the movement of the pencil, the pencil may be pushed forward, carrying the form with it, until an edge 53 of the form projects beyond the edge of the casing where it may be grasped by the operator.

The improvement of this invention resides primarily in the configuration of arresting pin 27 which accomplishes the initial arrest and alignment of the moving form. The pin is formed with a projecting edge 54 which extends above the remainder of the pin head. Consequently, when the pencil has been withdrawn from contact with pin 26 and both pins move upwardly under the action of the spring, only the projecting edge 55-54 of pin 27 engages the undersurface of the moving strip. Preferably, this edge 54 is not sharp, but is flattened slightly as at 55, to facilitate the movement of the paper over the edge, while the pin is riding on the paper. The corner 56, at which the flat 55 and the front face 57 of the pin meet, is rounded slightly to permit the corner from tearing the moving paper. Thus, this edge is free to snap into engagement with the filing hole as soon as the holes come into alignment with the edge. The remainder of the pin head does not contact the surface of the moving strip and, consequently, engagement of the projecting edge is immediate and is not delayed until the hole is in alignment with the entire head. The projecting edge 54 is formed on that portion of the pin head which is closest to the approaching form holes and the remainder of the head is slanted sharply downward and away from the edge.

Thus, after a salesperson has recorded a trans-

action on a form and he desires to remove the form from the register, he inserts the pencil 49 in a socket 50 of pin 26, pushes the pin downwardly and causes the simultaneous disengagement of both pins from the filing holes of the form. The operator then pushes the pencil forward along the channel 52. The form is carried forward with the moving pencil until the form edge 53 projects a short distance beyond the casing. This projecting edge is then grasped by the operator who removes the pencil from engagement with the pin and the holes of the form. After the pin has been removed, both pins tend to move upwardly under the action of spring 39 and the projecting edge 54 of pin 27 engages the bottom of the form. The operator then draws the form rapidly across the writing platen until the entire form is outside of the casing and the next form is in alignment on the platen, at which point the strip movement is arrested by the engagement of pin 27 with the holes in the following form.

It will be noted that during the movement of the strip only the projecting edge 54 of pin 27 rides the undersurface of the moving strip. The other portions of pin 23 cannot contact the strip because of the relief afforded by the slanted head, pin 26 does not contact the strip, since it is shorter than the projecting edge of pin 27 and its position relative to the strip is controlled by the engaged cams. Thus, since there is absolutely no interference with the upward movement of projecting edge 54 except the surface of the moving strip, which it alone contacts, the edge will snap into immediate engagement with the filing hole as soon as the filing hole comes into alignment with the edge. The arrest is not delayed until the entire pin is in alignment with the hole.

Having described my invention, I claim:

In combination with an autographic register of the type in which a strip of connected sets of superimposed forms, each form having a pair of filing holes therein, is moved across a writing

5 platen and each set of forms brought into successive registry with the platen, means for arresting the movement of the strip and for aligning the superimposed forms of each set when it is brought into registry with the platen comprising; a pair of pins, means interlinking said pins for simultaneous movement in a plane normal to the writing platen toward and away from set aligning positions in which the body portions of both pins are in snug engagement with the respective holes of a set of forms, spring means urging said pins toward set aligning positions, one of said pins configurated to receive an instrument for moving said pins away from set aligning positions and for initially advancing the strip, and the other of said pins having an arresting head extending beyond the body portion thereof so that the latter pin is adapted to ride on the surface of the strip when the strip is being moved across the platen holding the other pin in spaced relationship to the surface of the strip through said interlinkage means, said arresting head being smaller than the body portion of either pin and terminating in a blunt point, the end of which is adjacent the side of the pin facing oncoming forms and which is adapted to engage filing holes for arresting the strip in position of registry with the platen before the body portion of either pin engages the strip.

HARRY J. WAECHTER.
